CEMENTING MACHINE

Irving L. Keith, Haverhill, Mass.

Application August 21, 1936, Serial No. 97,128

1 Claim. (Cl. 91—47)

This invention relates to cementing machines of the horizontally disposed, vertically movable grid type, in which the grid is completely submerged in the liquid cement and then raised above the liquid level, so that the work to which the cement is to be applied may be laid on the top of the grid and the cement thereon may be transformed thereto.

The raising and lowering of the grid is performed either by a foot treadle, operated by the operator, or automatically by an electric motor, which operates cams so arranged that the grid is momentarily held practically stationary at the top of its movement and is quickly lowered and raised again during the rest of the revolution of the cams. As a result, a somewhat violent churning action takes place within the pan containing the adhesive, and, when the adhesive employed is rubber latex, this action causes the latex to foam, so that it often overflows from the pan containing it. Other objectionable results are also caused, such as covering portions of the work with the adhesive to which it should not be applied, and causing coagulation of the latex so that it becomes worthless as an adhesive. The same objectionable results also occur in connection with the treadle operated machines, although in a somewhat less degree, as the speed at which the grid is operated is usually less.

The use of latex in connection with the manufacture of shoes is, however, considered very desirable, on account of its low cost, as compared with many other adhesives, and the type of machine above referred to has been found to be the most practical for many of the cement applying operations necessary in connection with the manufacture of shoes.

The object of my invention is to provide a cementing machine of the above described type in which rubber latex may be employed, and with which foaming and other objectionable results due to the churning action of the grid, will be eliminated.

I accomplish this object by increasing the depth of the grid bars and relatively arranging the limits of movement of the grid so that the lower edge portions of the bars are not raised above the surface of the liquid at any time. Also by providing means for maintaining the liquid at a constant level, so that the limits of movement of the grid with relation to the liquid level may be constantly maintained and complete submergence of the grid when lowered will be assured at all times.

For a more complete disclosure of my inven-

tion reference is now made to the following specification, in connection with the accompanying drawing in which:

Fig. 1 is a top plan view of a cementing machine embodying my invention. 5

Fig. 2 is a sectional view at line 2—2 of Fig. 1.

Fig. 3 is an end view.

Figs. 4 and 5 are detail views illustrating the limits of movement of the grid with relation to the liquid level. 10

In the drawing, a supporting bench or table 10 is indicated, on the top side of which a liquid adhesive containing receptacle 12 is supported and to the underside of which a base 14 is attached. A horizontal shaft 16 is journaled in 15 bearings supported by said base and is adapted to be continuously driven by a motor 18 through a worm shaft 20 and a worm gear 22 on shaft 16. A cam 24 is mounted on shaft 16 at each end thereof, and a pair of rods 26 are mounted 20 to reciprocate vertically in guideways at each end of the base 14, said rods having rolls 28 at their lower ends which rest on the cams 24, so that, when shaft 16 is rotated said rods, will be reciprocated. 25

A grid 30 is supported by arms 32 on the top ends of rods 26, and may be of the type shown in my Patent #2,046,327 of July 7, 1936, being composed of a series of flat, parallel bars of uniform width and suitably spaced apart, the top edges 30 of said bars providing adhesive carrying faces which are arranged in the same horizontal plane, so that the bottom edges of said bars are at a uniform level.

Means are preferably provided for maintaining the liquid in the receptacle at a constant level. The means shown consist in providing the receptacle with an auxiliary reservoir 13 which opens directly into the receptacle and to which the liquid is fed by an inverted bottle 32, which 35 is supported by an adjustable bracket 34, on an upright 36 mounted on the support 10. The bottle is so arranged that the end of its neck is at the level of the liquid which is to be maintained, so that as the liquid is lowered in the receptacle 40 additional liquid will be supplied from the bottle in a manner which will be obvious. As thus arranged the liquid supplying means will not interfere with the work of the operator. 45

With the above described construction, when 50 the shaft 16 is driven, the cams 24 thereon will act to lift the grid so that the top edges of the bars thereof will be at approximately the level of the top edges of the receptacle, in which position said top edges will in practice be about $\frac{1}{4}$ of 55

an inch above the liquid level. In this position the lower edges of the bars will still be submerged in the liquid, as indicated in Figs. 2 and 4. The cams are preferably provided with a circular portion at the portion of greatest radius, so that there will be a slight dwell in the movement of the grid at the highest point to which it is lifted. As the cams are rotated from this position the grid is lowered by gravity to a position in which the top edges of the grid bars are at a substantial distance below the liquid level, as indicated in Fig. 5, so that they will be completely submerged in the liquid and will carry up a fresh supply when raised again.

15 As thus arranged, the grid is never completely withdrawn from the liquid, so that, when it moves downward, practically no air will be forced down into the liquid. Consequently all tendency to cause foaming, when rubber latex is employed as 20 an adhesive, will be avoided and the objectional results, before referred to, will not take place.

It will be understood that when treadle oper-

ated means for raising and lowering the grid are employed, the parts will be so arranged that the limits of motion of the grid will be substantially the same as that above described.

5 I claim:

In combination with a liquid adhesive containing receptacle, a horizontally disposed grid composed of suitably spaced bars of substantial width vertically and having faces on their top edges adapted to carry adhesive, and means for raising and lowering said grid within said receptacle and for so limiting the vertical movements thereof with relation to the liquid level in the receptacle that the grid is moved between a position in which it is completely submerged, so that adhesive is applied to said faces, and a position in which the lower edges of the bars are still submerged and the upper edges thereof are raised above the liquid level, to permit the work to be laid thereon and adhesive on said faces to be 10 applied thereto.

15 IRVING L. KEITH.
